US0D1021112S

(12) United States Design Patent (10) Patent No.: US D1,021,112 S
(45) Date of Patent: * Apr. 2, 2024

(54) TEETHER

(71) Applicant: Jingzhu Liang, Yangjiang (CN)

(72) Inventor: Jingzhu Liang, Yangjiang (CN)

() Term: 15 Years

(21) Appl. No.: 29/849,034

(22) Filed: Aug. 8, 2022

(30) Foreign Application Priority Data

Jul. 29, 2022 (CN) 202230489086.4

(51) LOC (14) Cl. 24-04

(52) U.S. Cl.

USPC D24/195; D4/107

(58) Field of Classification Search

USPC D24/193, 194, 195, 214; D1/101, 104, D1/199; D21/483, 496, 576, 609, 621, D21/628, 655; D30/160

CPC A61J 17/00; A61J 17/02; A46B 5/023; A46B 15/0097
